UNITED STATES PATENT OFFICE.

JOSEPH J. STOETZEL, OF NEW YORK, N. Y., ASSIGNOR TO G. & G. ATLAS SYSTEMS, INC.,
A CORPORATION OF NEW YORK.

SELF-REGULATING GRAVITY DISCHARGE TERMINAL.

Application filed May 23, 1924. Serial No. 715,300.

This invention relates more particularly to pneumatic despatch tube systems, of the open current type, but may be applied in other apparatus, when occasion arises. In such systems, as is well known, the carrier, speeding to its discharge terminal, or outlet, under the driving force of atmospheric air admitted behind the carrier, acquires considerable momentum in transit. If this momentum is not checked, cushioned, retarded, or otherwise guarded against, the carrier is apt to strike the outlet door with undesirable force, resulting at times in injury to the carrier, to the door, or other object, and, at all events, causing too much noise, in its delivery.

On the other hand, when the discharge door opens, either by pressure of the advancing air ahead of the carrier, or by the act of the carrier in striking the same, atmospheric air at once rushes in and this inrush is apt to thrust the carrier backward and thus delay its discharge or even pocket the carrier. In such case the carrier has to be manually removed. To overcome all these difficulties is the general object of my invention.

The specific means which I consider the best to accomplish this object are shown in the accompanying drawing, in which I have not found it necessary to illustrate any part of the pneumatic despatch tube system, itself, except the outlet terminal section, as the general construction of such systems is now pretty well understood by those familiar with the art.

The discharge terminal section shown consists primarily of the exhaust tube A, forming an H, by cross-tube B, and having a casing C,—and a discharge tube D, equipped with a self-closing door E.

The exhaust tube A, may be of the usual type, connected, above, with the usual transit system by which carriers are driven by air-pressure (usually atmospheric) from the cashier's station to the various salesman's stations, and back again during the operation of the system,—and connected, below, with an exhauster, of any suitable character, governed as to its speed by a suitable governor, in response to differences in the air-pressure within the transit system. The direction of flow of air through said tube is shown by arrows. Some flow in this direction is always maintained when the ex-

hauster is working but the quantity and pressure of the flow varies according to the requirements of the system.

The terminal door E, is preferably of light material and easily deflected by the pressure exerted upon the air in terminal tube D, when said carrier has passed downwardly below the cross-tube B. To this end I prefer to make the door E, overbalanced by the counterweight F,—and pivoted as at a, on a bracket mounted on the outside of casing C, in such manner that the downward pull of this counterweight F, tends at all times to keep said door E upon its seat and to return the same to its seat whenever displaced,—that is, opened or partly so, in the direction of the curved arrow-line.

The discharge tube D, preferably passes through the casing C, as shown, but has no communication with the interior of said casing except by means of the cross tube B, and exhaust tube A.

The casing C, has a port G, by which atmospheric air may be admitted to said casing, when occasion requires, and thence to the exhaust tube A, both above and below said casing. This port G, is normally closed by the door E, but is instantly responsive to any opening, however slight, of said door.

The operation of my improved discharge terminal as applied to an open current or vacuum system of pneumatic despatch tubes is as follows:

When no carrier is in line, the entire system is idle except for a slight flow of air which moves in the direction of the arrows in response to a continued running of the exhauster at minimum speed. This slight flow of air is at atmospheric pressure, and permeates the entire terminal shown. That portion of the air, which fills the tube D, may be regarded as static, under these conditions.

Upon the insertion of a carrier in the system at whatever point above the section exhaust tube shown in the drawing, the system becomes temporarily closed against the atmosphere between the point of said insertion and the exhauster. It will, of course, be understood that a suitable air-control valve is located somewhere in the exhaust tube A, below the circle marked V, and above the exhauster. This control valve, if properly constructed, will at once open upon the insertion of the carrier in question, wide

enough to permit the exhauster to speed up and exhaust the air ahead of said carrier to the predetermined rarefaction, usually expressed as one pound of vacuum.

- 5 In instant response to this action on the part of the exhauster, the atmospheric air behind the inserted carrier will begin to push the carrier toward its destination at a speed of approximately twenty-five feet per second. This movement of the carrier will 10 push all the rarefied air before it toward the terminal shown in the drawing, (and thence to the exhauster) at its own speed of travel. The direction of flow through the exhaust tube will, as before stated, be in the direction of the arrows, that is through cross tube B, casing C, to the exhauster. The air in tube D will still be static but rarefied to the same degree as that in the exhaust tube A.
- 20 This condition will continue until the carrier has reached the mouth of the cross-tube B. The momentum of the carrier will be sufficient to carry it past the mouth of the cross tube and the carrier will, therefore, 25 compress the static air in tube D until the pressure becomes great enough to open the discharge door E. When this takes place the carrier will pass, by its own gravity, quietly 30 out of the tube D and fall into any receptacle which may be awaiting the carrier, below.

Meanwhile, as soon as the carrier passes the mouth of the cross-tube B, the full rush of atmospheric air which was behind the 35 carrier and driving it forward, will become free to pass directly through tube B, casing C, and the rest of exhaust tube A to the exhauster. Unless there is another carrier in line following the first carrier. In such case, 40 of course, the atmospheric air between the two carriers will be speedily exhausted and the second carrier will assume the speed of the first.

If the first carrier were still in the tube D, 45 when this exhaustion takes place, there would be a back draft upon said first carrier through the cross-tube B. To prevent this back draft occurring, I provide the port G direct from atmosphere to casing C. This 50 port, normally closed by the door E, is automatically opened by the opening of the door E, even to but a small extent,—a mere crack,—and, so opened, permits an inrush of atmospheric air to casing C, sufficient, not 55 only to prevent any back-draft upon carrier in tube D, but to hasten the exit of said carrier by the door E, if necessary.

Another function of the port G, is to 60 quicken the action of the control-valve located between the casing C, and the exhauster. This it does by supplying free air to the exhaust tube nearer the exhauster than the cross-tube B, and thus cutting down the speed of the exhauster sooner than would

be the case if the control-valve depended for its action solely upon air coming from the bell-mouth through the entire length of tubing.

Where there is more than one carrier in transit, the admission of air through port G, 70 by opening door E, tends to prevent the following carriers from too violent an increase of speed upon the discharge of a preceding carrier.

As soon as the last carrier in line has 75 passed out of line at the discharge terminal, the control-valve will reestablish the normal idle conditions as will be readily understood. This normal condition will, of course, persist until a new carrier is inserted somewhere in the line when the operation above described will be repeated.

I claim:

1. In a carrier delivery device for pneumatic dispatch systems, a transit tube, an exhaust tube having its receiving end portion mounted in adjacent and parallel relation to the delivery end portion of the transit tube, a cross-tube connection between the end of the exhaust tube and a point in the transit tube spaced from the end thereof, a gate hinged to the delivery end of the transit tube, a hinged connection of the gate with the tube being located at the edge of the transit tube remote from the exhaust tube, the hinged end of the gate being extended and provided with a weight normally tending to close the gate, said exhaust tube being provided with an air inlet port adjacent the delivery end of the transit tube, said gate member being extended at its free end to close the inlet port in the exhaust tube when in closing relation to the end of the transit tube.

2. In a carrier delivery device for pneumatic dispatch systems, a transit tube, an exhaust tube having its receiving end portion mounted in adjacent and parallel relation to the delivery end of the transit tube, a cross-tube connection between the end of the exhaust tube and a point in the transit tube spaced from the end thereof, a hinged gate attached to the terminal edge of the transit tube remote from the exhaust tube, 100 said gate occupying an inclined position and provided with a weight for moving the gate to closed position, the terminal end of the transit tube being wholly closed at the gate whereby no communication is provided between the delivery end of the transit tube and the exhaust tube, said exhaust tube being provided with an air inlet port adjacent the delivery end of the transit tube, said hinged gate having an extension arranged 105 to close the inlet port when the hinged gate is in closing relation to the delivery end of the transit tube.

JOSEPH J. STOETZEL.
